UNITED STATES PATENT OFFICE.

EDWIN HART, OF WATERBURY, CONNECTICUT, ASSIGNOR TO THE
WATERBURY WATCH COMPANY, OF SAME PLACE.

DESIGN FOR A CYCLOMETER-BRACKET.

SPECIFICATION forming part of Design No. 28,590, dated May 10, 1898.

Application filed March 24, 1898. Serial No. 675,043. Term of patent 14 years.

To all whom it may concern:

Be it known that I, EDWIN HART, of Waterbury, in the county of New Haven, and in the State of Connecticut, have invented a certain new and original Design for a Cycloometer-Bracket; and I do hereby declare that the following is a full, clear, and exact description thereof, reference being had to the accompanying drawings, in which—

Figure 1 is a perspective view of a bracket embodying my design; Fig. 2, a side elevation thereof, and Fig. 3 an end elevation.

Letters of like name and kind refer to like parts in each of the figures.

The object of my invention is to provide a new shape for brackets for attaching cycloometers to bicycles; and to this end said invention consists in the design for a bracket, substantially as herein set forth.

The leading feature of my design is the shape of the object-gripping part of the bracket, which consists of two lugs projecting laterally from the shank or main part of the bracket, with their similar ends bent or turned inward toward each other.

The bracket, as shown, consists of a shank or main part A, with one end rounded, with an elongated opening a near such end, and

reduced in size above said opening, the outline of its sides where such reduction takes place being formed of compound curves. At its other end the shank A has projecting at right angles from it two parallel lugs B and B, that at their similar opposite ends b and b are bent inward toward each other, each being on a curve that merges into a concavely-curved contour that is given the edge of that end of the shank A from which the lugs extend. Each of the lugs B and B has an opening b' and a rounded corner on the end opposite the curved end b. Between the two lugs B and B the part A has a slit a', extending parallel with them, that terminates in a round opening a'.

Having thus described my invention, what I claim is—

The design for a bracket, substantially as shown and described.

In testimony that I claim the foregoing I have hereunto set my hand this 16th day of March, 1898.

EDWIN HART.
